United States Patent Office.

THOMAS D. STETSON, OF NEW YORK, N. Y., ASSIGNOR TO THE HEATH & SMITH MANUFACTURING COMPANY, OF PORTLAND, CONNECTICUT.

Design No. 4,936, dated May 23, 1871.

DESIGN FOR STREET-LAMPS.

The Schedule referred to in these Letters Patent and making part of the same.

To all whom it may concern:

Be it known that I, THOMAS D. STETSON, of the city and county of New York, State of New York, have invented a certain new and improved Design for Street-Lamps.

The accompanying drawings form a part of this specification, and show my improved design very clearly.

The globe D, of glass, carries a suitable ornamental top, and is encircled by a ring, B, with curved arms B¹ and internal branches B², the latter reaching inward under the lower edge of the globe D.

The gas-pipe is represented by a.

The general effect is symmetrical and tasty, the spherical or nearly spherical globe D protruding above

the more extended contour of the figure, described by the curved arms B, as an acorn sits in its cup.

Figure 1 is a side elevation of the entire lamp, and Figure 2 is a plan view with the glass and top removed.

Similar letters of reference indicate like parts in both the figures.

I claim—

The improved design for street-lamps, as shown in the figure.

In testimony whereof I have hereunto set my name in the presence of two subscribing witnesses.

Witnesses: THOMAS D. STETSON.

C. C. LIVINGS,

A. HOERMANN.
